(Cl. D56—4)

To all whom it may concern:

Be it known that I, Alexander H. Girard, a citizen of the United States of America, residing in Grosse Pointe, in the county of Wayne and State of Michigan, have invented a new, original, and ornamental Design for Combination Radio and Phonograph Cabinet, of which the following is a specification, reference being had to the accompanying drawing forming a part thereof, wherein:

Fig. 1 is a perspective view of a combination radio and phonograph cabinet showing my new design;

Fig. 2 is a rear elevational view thereof; and
Fig. 3 is a side elevational view thereof.

I claim:

The ornamental design for a combination radio and phonograph cabinet, as shown.

ALEXANDER H. GIRARD.
